UNITED STATES PATENT OFFICE.

GEORGE H. KENDALL, OF NEW YORK, N. Y.

DESIGN FOR BUSINESS-CARDS.

Specification forming part of Design No. **11,553**, dated December 30, 1879; application filed October 15, 1879.
[Term of patent 3½ years.]

To all whom it may concern:

Be it known that I, GEORGE H. KENDALL, of New York city, have originated a novel Design for a Business-Card, of which the following, in connection with the adjoined drawing, is a full, clear, and exact description.

My design consists in a novel, attractive, and artistic device to be printed on one of the faces of a business-card, or for other analogous use.

The annexed drawing illustrates the ornamental face of a flat business-card printed according to my design.

The card on which my design is to be printed I prefer to cut in the form of a hand-mirror, as shown, and the face is printed around its margin with a design or figurement representing the frame and handle of a hand-mirror. The space within the frame representing the reflecting-surface of the mirror may have

a portion left plain and bright to indicate the mirror-surface, or it may be shaded or tinted to give the same effect, and it also contains a picture of a face or other form representing a reflection therefrom, as illustrated. The reverse side of the card is left plain.

The card as thus designed presents a novel and pleasing effect, and is well adapted for an artistic and attractive business-card.

What I claim as new is—

A design for printing on business-cards, consisting of the representation of a hand-mirror with ornamental frame and handle, and having on the part indicating the glass a device simulating a reflected figure, substantially as herein shown and described.

GEORGE H. KENDALL.
